UNITED STATES PATENT OFFICE.

NARCISE DUOIRE, OF WATERVLIET, NEW YORK, ASSIGNOR, BY MESNE ASSIGNMENTS, TO MARY ELLA VAN OSDEL, OF CHICAGO, ILLINOIS.

STUFFING-BOX.

SPECIFICATION forming part of Letters Patent No. 464,935, dated December 8, 1891.

Application filed February 18, 1889. Renewed June 8, 1891. Serial No. 395,439. (No model.)

To all whom it may concern:

Be it known that I, NARCISE DUOIRE, a citizen of the United States, residing at Watervliet, in the county of Albany and State of New York, have invented a new and useful Improvement in Stuffing-Boxes, of which the following is a specification, reference being had to the accompanying drawings, in which—

10 Figure 1 is a longitudinal section. Fig. 2 is a cross-section at line 2 of Fig. 1, partly broken out. Fig. 3 is a detached and enlarged wood section.

The object of this invention is to improve 15 the construction and operation of stuffing-boxes for steam piston-rods, pump and valve rods, and for such other uses as require stuffing-boxes; and its nature consists in the improvement hereinafter described and claimed 20 as new.

In the drawings, *a* indicates the stuffing-box.

a' is an end flange.

b is part of an end plate for a steam or 25 other cylinder.

c is the pressure-plate or end cap.

d is a section of a piston-rod.

e are bolts.

f are ungrooved disks or rings.

30 *g* are wood sections used in forming wooden rings.

h is an interior groove in the wooden sections.

i are lead rings.

35 The stuffing-box *a*, with this cap *c*, is made in the usual manner, the cap being bolted to the flange *a'* by the bolts *e* in the usual manner. In forming the interior of the stuffing-box I first apply an ungrooved ring *f*, and 40 then apply two or more grooved wooden sec-

tions *g*, cut with the grain of the wood, as indicated in Fig. 3. I then apply another ring, against which the inner projection of the cap or pressure-plate *c* rests with such pressure, as may be given it by the screws or bolts *e*. 45 For a stuffing-box of considerable length it will be advisable to interpose the rings *f* between the grooved ones; but for a short one the grooved rings may be placed together, as shown. I form my rings of sections cut side- 50 wise with the grain for the purpose of obtaining the advantage of the swelling of the wood when steam or water is applied to move the piston-rod *d*, and in this manner I obtain a perfectly tight packing for the box. 55

In order to obtain a further improved wearing-surface for the packing so formed, I groove the wood sections, as shown in Figs. 1 and 3, and fill the grooves with lead, Babbitt metal, or other soft metal suitable to form a 60 wearing-surface for a piston-rod, and thus, when the wooden sections are placed in position, additional soft-metal rings are formed as a part of the packing around the piston-rod, which gives an improved bearing and 65 wearing surface for such rod. The rings *f* may be made of ungrooved or solid wood sections cut with the grain of the wood, as described, and, if desired, the end rings may be made of metal. 70

What I claim as new, and desire to secure by Letters Patent, is—

In a stuffing-box, the combination of the wood sections *g*, formed as described, with the lead sections or rings *i* and disks *f*, substantially as and for the purpose specified. 75

NARCISE DUOIRE.
